UNITED STATES PATENT OFFICE

JAYSON K. BOND, OF MILWAUKEE, WISCONSIN, ASSIGNOR TO FEDERAL ASBESTOS & CORK INSULATION CO., OF MILWAUKEE, WISCONSIN, A CORPORATION OF WISCONSIN

FLORAL CASE

Application filed June 15, 1928. Serial No. 285,751.

This invention relates to improvements in floral cases, and more particularly to an illuminated refrigerated floral display case.

It is one of the objects of the present invention to provide a refrigerated display case equipped with concealed illuminating means for the main compartment of the case, said illuminating means being arranged so that heat generated thereby cannot get into nor affect the temperature of the main refrigerated compartment.

A further object of the invention is to provide, in a case of the class described, means for illumination which will give novel and attractive coloring effects.

A further object of the invention is to provide an illuminated refrigerated case in which the lights are mounted adjacent an upper inclined wall, the lights being concealed and in the path of a rising warm air current, whereby no counter currents are set up.

A further object of the invention is to provide a floral case having an upper, vented, auxiliary display compartment with illuminating means therein, said illuminating means being common for both said auxiliary compartment and the main refrigerated compartment and the heat therefrom passing out of said vented auxiliary compartment.

A further object of the invention is to provide a display case of the class described in which the interior walls of the main compartment are mirrored and the side walls are rearwardly converging, giving to the case an effect of greater depth and dimensions.

A further object of the invention is to provide a display case in which space at the upper front portion, ordinarily wasted, is utilized as an auxiliary compartment, the same being shallow but having a mirrored rear wall to give the effect of depth.

A further object of the invention is to provide an illuminated refrigerated upright case which is of simple construction, has a large capacity, is neat and attractive in appearance, effectively displays goods therein, and is well adapted for the purposes described.

With the above and other objects in view the invention consists of the improved illuminated display case, and its parts and com-

bination as set forth in the claims, and all equivalents thereof.

In the accompanying drawings in which the same reference characters indicate the same parts in all of the views:

55

Fig. 1 is a front view of the improved floral case;

Fig. 2 is a vertical sectional view taken on line 2—2 of Fig. 1;

Fig. 3 is a cross sectional view taken on line 3—3 of Fig. 2; and

Fig. 4 is a cross sectional view taken on line 4—4 of Fig. 2.

Referring now more particularly to the drawings it will appear that the improved 65 show case is of the upright type and is formed with a bottom 6, a rear 7, sides 8, and a top 9, all of these portions being formed of several thicknesses, including layers of cork insulating material, as shown. Intermediate the 70 top and bottom of the case there are horizontal transverse braces 10 and 25 dividing the interior of the case into a main display compartment 11 and an upper communicating 75 storage compartment 12 in which the refrigerating coils or ice loft may be positioned.

The front of the main compartment is formed with rails providing a pair of side openings which are normally closed by hinged doors 13, the major portions of which are 80 of three thicknesses of glass for visibility and insulation. Between said doors the space is closed by a window or glazed member 14.

The front of the upper storage compartment 12 is closed by a vertical insulating wall 85 15, inwardly of the front edge of the show case and extending from the braces 10 to the top 9. The front surface of the wall 15 has mounted therein mirrors 16. There is, 90 therefore, provided forwardly of the upper storage compartment 12 an upper unrefrigerated display compartment 17 having an open upper end portion, as shown in Figs. 2 and 3. A horizontal glass shelf 18 is mounted 95 within said compartment whereon containers or receptacles displaying goods may be stationed. The front portion of said compartment 17 may be open, but is preferably of a rail construction, as shown, and is closed 100

by a pair of sliding glass doors 19 and a central window 20.

5 Positioned adjacent the lower edge of the wall 15 is a longitudinally extended rail 21 having an angled front edge. Spaced forwardly of and below said rail 21 are a pair of adjacent rails 22 having their rear faces inclined, and mounted in spaced relation to the inclined edges of said rails 21 and 22 are 10 a plurality of sheets of glass 23 forming a multi-layered, inclined window between the compartments 11 and 17. If desired, one or more of the sheets of glass 23 may be colored to give novel lighting effects. Positioned 15 above the glass 23 is a removable, elongated horizontal glass sheet 24 and mounted in the compartments formed between the glasses 23 and 24 in the brace members 25 are electrical sockets 26 carrying incandescent bulbs 27. 20 This arrangement provides for the illumination of the compartments 11 and 17 and the illuminating means are concealed by the front rail 28. Also, heat generated by said bulbs is insulated from the main refrigerated compartment 11 by the spaced apart glass sheets 23, but can be dissipated through the open 25 upper end portion of the compartment 17.

It should be observed that the inner surface 30 of the rear 7, within the main compartment 11, is covered by a mirror 29 and the sides 8 are covered by rearwardly converging mirrors 30. This mirror arrangement will reflect the goods within the compartment and also give the effect of greater depth and volume. 35 Within the compartment 11 are a plurality of horizontal shelves 31.

There is a slidably mounted tray 32 within the upper storage compartment 12 and one end portion of said compartment is provided 40 with a hinged door 33 to provide access to the same.

The improved show case is especially suited 45 for florists' purposes and provides a main refrigerated display compartment, an upper storage compartment, and an upper front display compartment. Both display compartments are effectively illuminated by concealed 50 means and the heat therefrom is carried off and does not influence the refrigerated compartments. Also, the mirror arrangements add to the attractiveness of the case. Furthermore, the show case is of simple and novel construction and is well adapted for the purposes set forth.

55 What I claim as my invention is:

1. A refrigerated show case, comprising bottom, top, rear and side walls, glazed doors and windows closing the front of said case, a vertical wall inwardly of the front of the case 60 and extending downwardly from the top and terminating intermediate the top and bottom, said wall defining an upper forward compartment, the top of the same being open, and a main refrigerated compartment, and 65 an angularly disposed multi-layered window

between said compartments, the front of the case having an elongated rail thereadjacent, the arrangement being adapted to permit the mounting of an incandescent bulb within the upper compartment between said rail and the 70 window for illuminating both compartments.

2. A refrigerated show case, comprising bottom, top, rear and side walls, glazed windows and doors closing the front of said case, a vertical wall inwardly of the front of the 75 case and extending downwardly from the top and terminating intermediate the top and bottom, said wall defining an upper forward compartment, the top of the same being open, and a main refrigerated compartment, all of 80 the inner walls of said main refrigerated compartment being mirrored and the side walls of the same being rearwardly converging, and an angularly disposed multi-layered window 85 between said compartments, the front of the case having an elongated rail thereadjacent, the arrangement being adapted to permit the mounting of an incandescent bulb within the upper compartment between said rail and the window for the illumination of 90 both compartments.

In testimony whereof, I affix my signature.

JAYSON K. BOND.
